Inventor

UNITED STATES PATENT OFFICE.

ISAAC N. KENDALL, OF NEW WESTMINSTER, CANADA.

PULLEY.

SPECIFICATION forming part of Letters Patent No. 453,315, dated June 2, 1891.

Application filed November 21, 1890. Serial No. 372,199. (No model.)

To all whom it may concern:

Be it known that I, ISAAC N. KENDALL, a citizen of the United States, residing at the city of New Westminster, in the district of 5 New Westminster and Province of British Columbia, Canada, have invented a new and useful Pulley, of which the following is a specification.

This invention has relation to pulleys of 10 that class adapted to be used in connection with rope or wire cable.

The objects in view are to provide a pulley which will automatically grasp the rope or cable at one portion of its revolution and release the same at the remaining half of its 15 revolution; to provide means for gripping and releasing the rope automatically, and, furthermore, to provide means for compensating for wear.

With the above objects in view the invention consists in certain features of construction hereinafter specified, and particularly 20 pointed out in the claims.

Referring to the drawings, Figure 1 is a 25 vertical longitudinal section of a shaft and a pulley constructed in accordance with my invention mounted thereon. Fig. 2 is a face view of the pulley. Fig. 3 is a detail in perspective of the bearing for one end of the 30 shaft. Fig. 4 is a similar view of the sliding collar.

Like numerals of reference indicate like parts in all the figures of the drawings.

1 designates a shaft mounted at one end in 35 a bearing 2, lined with Babbitt metal. 3 designates the opposite bearing, the rear end being extended in rear of the bearing proper and upwardly turned to form an end wall 4, having a central opening 5, in which is mounted 40 a brass centrally-bored and threaded bushing 6, the inner end of which is beyond the inner surface of the end wall 4 and is provided with an annular flange 7. Between the annular flange 7 and the inner face of the wall 45 4 a rubber ring or washer 8 encircles the bushing, and threaded in the bushing is a screw 9, terminating at its inner end in a head or bearing-point and provided at its outer end outside of the bushing with a hand-wheel 10. In 50 front of the bearing proper 3 and in line therewith there is located and integrally

formed therewith a hollow centrally-bored tube or bearing 11, the rear end of which is provided with an annular flange 12. The interior of both bearings 3 and 11 are provided 55 with linings of Babbitt metal. Between the inner end of the tube or bearing 11 and the bearing 2 there is keyed upon the shaft the circular concavo-convex shell or casting 13, which upon its concave side is provided 60 with a half-groove 14. At intervals the inner or concave face of the shell is provided with pairs of bearing-ears 15, and between each pair of bearing-ears there is pivoted upon a pintle 16 a clamping-lever 17, the outer 65 end of which upon its inner side is provided with half a groove 18, combining with the groove 14 near the shell, and the inner end of which occurs short of the center of the shell. Trunnions 18^a are located at the opposite 70 sides of the levers, and said trunnions are perforated to receive the aforesaid pintles. The levers are wedge-shaped or widened toward their ends, and between the levers there is cast to the face and near the edge of the 75 shell half-grooved projections or lugs 19. These projections or lugs are duplicated between the inner ends of the levers, as shown at 20.

21 designates a sleeve mounted for sliding 80 upon the tube or sleeve 11. The sleeve 21 is provided at its rear end with an annular flange 22, provided at intervals with perforations 23, which occur opposite similar perforations formed in the annular flange 12. The 85 two flanges are connected by means of screws or bolts 24, passing through the perforations 23, and between the two flanges upon each bolt is mounted a set-nut 25. By operating these nuts the sleeve 21 may be fed to or from 90 the pulley. At its inner end the sleeve 21 is provided with an annular flange 26, which extends above the inner ends of the clamping-levers, as shown. The upper portion of the flange 21 is provided with a rearwardly 95 extended track 27, said track extending round the flange for about one-half its circumference, and over the track and the flange ride the inner ends of the clamping-levers.

This being the construction, the operation 100 is as follows: As the shaft 1 revolves it carries with it the shell or pulley 13, and the in-

ner ends of the levers 17, riding over the raised track 27, cause the outer ends of the levers when in this position to be pressed toward the shell, and thus a cable or rope located in the grooves 14 and 18 is securely clamped and prevented from slipping. This clamping of a lever upon the table continues for half a revolution, or until the same arrives opposite the point where the cable passes upon the pulley, said clamping being maintained until the end of the track 27 is reached, when the lever is released from the track and the remainder of the revolution passes around the face of the flange 26, so that as one lever is thrown into a clamping position at the upper side of the pulley another lever is releasing the cable at the lower side of the pulley. In this manner it will be apparent that all slipping of the cable or rope is absolutely avoided and the engagement of the rope to the cable made positive.

It will be apparent that in time the track 27 and the ends of the levers will become worn, and for this reason I provide the adjustment described. By operating the wheel 10 the screw 9 is fed forward, and thus forces the shaft and the shell away from the sleeve 21, so that the wear of the parts will be fully compensated for and the durability of the device is greatly increased. By operating the nut 25 a final adjustment may be obtained for the purpose of adjusting the levers 17. By reason of the rubber packing 8 it will be apparent that the shaft is permitted to move slightly in cases where splices or other enlargements pass over the pulley, and therefore danger of breaking the parts is avoided.

Having described my invention, what I claim is—

40 1. The combination of the grooved pulley and a series of levers fulcrumed upon the face of the pulley and having the outer ends thereof provided with grooves opposite the groove of the pulley, and an adjustable non-rotating sleeve provided at its inner end with a flange having a track for engaging the inner ends of the levers, substantially as specified.

2. The combination, with the pulley, the side of which is grooved, and the series of 50 clamping-levers fulcrumed upon the face of the pulley and grooved near their outer ends, of a sleeve mounted for longitudinal adjustment upon the same, and a flange provided with a track for operating against the inner 55 ends of the levers and mounted upon said sleeve, substantially as specified.

3. The combination, with the pulley, its shaft, the clamping-levers, and means for operating the same, of the bearing for one end 60 of the shaft, a set-screw supported in the bearing and bearing against the end of the shaft, a bushing encircling the set-screw and provided upon its inner end with a flange, and a rubber or other yielding packing encircling 65 the bushing and interposed between the same and the end of the bearing, substantially as specified.

4. The combination, with the pulley-shell, of the series of pairs of bearing-lugs secured to 70 the face of the same, the series of levers pivoted between the bearing-ears, the grooved lugs 19 and 20, located between the levers, the bearing 3 for the end of the shaft, the shaft 1, the tube or sleeve 11, having the 75 flange 12, the sliding sleeve 21, splined upon the sleeve 11 and provided with the rear flange 22 and the front flange 26, having the track 27 for operating the levers, the bolts 24, connecting the rear flanges of the two sleeves, 80 the nuts mounted upon the bolts between the flanges, the headed bushing 6, located in the rear end of the bearing 2, the adjusting-screw threaded in the bushing, terminating at its inner end against the shaft and at its outer 85 end provided with a hand-wheel, and the rubber packing 8, interposed between the head of the bushing and the bearing, substantially as specified.

In testimony that I claim the foregoing as 90 my own I have hereto affixed my signature in presence of two witnesses.

ISAAC N. KENDALL.
